UNITED STATES PATENT OFFICE

2,437,767

SLEIGH

Donald W. Thompson, Windham, N. Y., assignor to Thompson Brothers, a copartnership composed of Ferris B. Thompson, Raymond H. Thompson, and Donald W. Thompson, all of Windham, N. Y.

Application April 2, 1945, Serial No. 586,057

1 Claim. (Cl. 280—19)

1

This invention relates to sleighs for hauling heavy loads and especially to sleighs used for logging and lumbering operations and it has for its main object to provide a simple and inexpensive but strong and durable sleigh which is so designed that it may be constructed entirely or almost entirely of metal and in which the parts are joined with great flexibility so that a greater maneuverability can be obtained resulting in a greater ease and greater security with which the sleigh may be guided and directed when hauling heavy loads through the woods.

Sleighs for the hauling of heavy loads have always been made of wood and in order to be able to obtain a good maneuverability the entire construction has to be made as rigid as possible. The elasticity of the wood is limited and can, therefore, not be relied upon to take care of bumps and shocks due to heavy loads and large forces of inertia. The wooden sleighs, therefore, were so designed that a completely rigid structure is formed which always acts as a unit withstanding as a whole the heavy strains put upon it by shocks and bumping of the load and by the forces of inertia due to the speed acquired.

The present invention has mainly reference to sleighs of the type referred to which are made of steel girders, steel plate and similar metal parts and it is based on the fact that suitable flexible or pivotal connection will give a greater flexibility to the structure, without detracting from its solidity.

Flexibility without loss of solidity may be obtained by providing a plurality of fixing means between the main parts of the sleigh, some of which hold the parts firmly together, while others provide the necessary amount of relative movement. This results in a higher flexibility of the entire structure in a more independent adjustment of the two sides and, therefore, in a better adjustment to the inequalities and the change of direction of the path along which the sleigh is moving. By virtue of this adjustment a higher maneuverability of the loaded sleigh may be obtained which is of great advantage.

According to the invention these results are obtained by joining the bolster or cross-bar, which runs transversely from runner to runner with the latter by two different means. One of these means consists in a pivot bolt, while the other comprises a band or bands holding the bolster firmly against vertical displacement. This double fixation will provide the necessary rigidity and solidity of the connection while permitting at the same time a certain amount of independent movement of the runners.

A further increase of the transverse rigidity is obtained by a reinforced tongue and tongue holding structure. Individual movements of the runners and other parts bring into play the high

elasticity of the steel of which the parts are formed and these elastic powers will greatly add to the ease and security with which the sleigh may be handled during its run through the woods.

The invention is illustrated in the accompanying drawings in which:

Figure 1 is a plan view of the sleigh.

Figure 2 is a side view thereof.

Figure 3 is a longitudinal cross-section through the sleigh.

Figure 4 is a cross-section through the sleigh in a transverse direction along line 4—4 of Figure 1.

15 Figure 5 is a view of the tongue and the tongue holder.

The sleigh, as illustrated in the drawings, comprises the runners 11 which, as customary, are slightly bent upwardly in their foremost part to

20 form the so-called bang iron 30. The bolster or cross-bar 12 is mounted transversely on said runners. These parts are both made of steel girders of a suitable cross-section. The bolster 12 is seated on bolster blocks 13 and is firmly

25 held on the block by means of bands 14 fixed on the runners 11 by means of screws 15 or rivets. The bands 14 are preferably running over flat parts of the bolster 12 and when the latter is provided with upturned flanges 16 as shown in

30 the drawings, these flanges are cut away for a certain length in order to permit a firm hold of the bands on the surface of the bolster. The bolster may be provided with holes 19 at its ends through which the ropes attaching the load are

35 drawn.

A bolt 17 passes through the bolster 12, the bolster block 13 and the band 14, joining these parts. It is provided with an end portion passing through a bore in and held by the runners 11.

40 This bolt forms a pivot permitting a certain limited motion between the parts joined by the bolt.

In the fore-part of the sleigh the runners are connected by the so-called "roller," which in the example illustrated, consists of a strong axle bar 45 20 to which the tongue holder 21 is fixed. The ends 28 of the axle bar are held in holes 29 provided in the upturned ends 30 of the runners.

The tongue holder 21 is much stronger than the corresponding structures in known constructions. It consists of a triangular sheet 22 reinforced at its lateral edges by bands 23 and further reinforced in the middle by a cross-band 24. The tongue 25 is fixed to the sheet in any appropriate manner, for instance, by rivets or screws 55 or by welding and preferably reaches down to the cross-band 24, thus reinforcing the foremost part of the entire tongue holder. The rear end of the tongue holder is provided with sleeves 26 encircling the axle bar 20. At the front end of the 60 tongue the customary eye 27 is attached.

It is seen from the above description that the sleigh according to the invention provides a very strong construction which is nevertheless yielding so that it will be able to accommodate and adjust itself to the inequalities of the track. Dangerous transverse inclinations of the load are, therefore, less frequent as full use can be made of the elasticity of the members without impairing the solidity and the rigidity of the entire construction.

What I claim is:

In a sleigh for logging and lumbering operations consisting of steel girders, runners consisting of I-irons, a bolster consisting of an I-iron provided with two flattened portions, bolster blocks consisting of H-irons cut to a trapezoidal shape and having a seating surface on the runners equal to the width of the same and an enlarged upper surface for seating the bolster, means for fixing said bolster and blocks simultaneously on the runners by means of a joint-like connection said means comprising a band for each side, fixed to the upper flanges of the I-iron forming the runner, and passing over

the flattened portions of the bolster, and a bolt passing through said band, bolster and bolster block inclined with respect to the runner and fixed on one flange thereon, said bolt and band clamping the above-named parts firmly together while permitting a relative twisting movement around the bolts between them.

DONALD W. THOMPSON.
